UNITED STATES PATENT OFFICE.

JOHN FRICK, OF PHILADELPHIA, PENNSYLVANIA, ASSIGNOR TO AMERICAN AUTOMATIC SODA FOUNTAIN COMPANY, OF CHARLOTTE, NORTH CAROLINA, A CORPORATION OF NORTH CAROLINA.

LIQUID-DISPENSING APPARATUS.

1,366,529.

Specification of Letters Patent. Patented Jan. 25, 1921.

Original application filed July 23, 1919, Serial No. 312,806. Divided and this application filed December 31, 1919. Serial No. 348,669.

To all whom it may concern:

Be it known that I, JOHN FRICK, a citizen of the United States, residing at Philadelphia, county of Philadelphia, and State of Pennsylvania, have invented a new and useful Improvement in Liquid-Dispensing Apparatus, of which the following is a full, clear, and exact description, reference being had to the accompanying drawings, which 10 form a part of this specification.

The object of my invention is to provide a soda water vending machine, adapted to dispense a measured quantity of flavoring syrup and a measured quantity of carbonated water, under pressure, into a properly positioned cup.

The mechanism whereby the above objects are attained is intended more particularly to be coin-controlled, and means whereby 20 the deposit of a coin renders said mechanism operative are shown, but the mechanism is readily adaptable for use independently of coin control.

In an application filed by me July 23, 25 1919, Serial No. 312,806, of which this application is a division, I have fully disclosed the present invention in association with coin-controlled means for delivering a cup; the syrup and carbonating water dispensing 30 mechanism being shown as depending for its operation upon the prior successive operations of inserting a coin and operating the cup delivery mechanism to deliver a cup and release the coin, and the coin then so 35 positioning itself as to render the syrup and water dispensing mechanism operative. In the present application, I have disclosed only the mechanism for dispensing syrup and water, together with a coin duct leading 40 to said mechanism.

In the drawings, which show a preferred embodiment of my invention:

Figure 1 is a side elevation of the machine.

Fig. 2 is an enlarged elevation, partly in section, of a part of the mechanism.

Fig. 3 is a rear elevation of the mechanism of Fig. 2.

Fig. 4 is a plan view of the carbonated water cooling and measuring device.

Fig. 5 is a side view of part of the mechanism immediately controlled by a coin.

Fig. 6 is a plan view of the coin discharge chute.

Fig. 7 is a perspective view of cam shaft 55 and attached and immediately coöperating parts.

Fig. 8 is a detail view of the discharge for the carbonated water.

Fig. 9 is a vertical section through the 60 syrup reservoir.

I shall first describe the carbonated water cooling, measuring and delivering element. Within the casing *a* is an insulated tank *b*, adapted to be iced, in which are suitably 65 mounted the horizontal cylinders *c* connected together by a pipe *d* and connected to a supply of carbonated water *e*. Within the tank is located an upright cylinder *h* inclosing a tight fitting plunger *i* carried by a 70 screw *j* threaded in the cylinder head and retained in any desired position by means of a lock nut *k*.

A pipe *l* connects one of the horizontal cylinders *c* with a passage *y* in the upper 75 part of a valve casing *m*. A pipe *n* leading from the lower part of the valve casing has a Y branch leading to the bottom of cylinder *h*, the main line extending upward and out of the tank *b* and terminating in a valve *o*. A pipe *p* leads from the lower part of the valve casing and terminates in a muffler *q*. Small holes *r* in the side of the pipe allow communication from the pipe to the muffler. A pipe *s* leads from the muffler, 85 out through the casing *a* and terminates at a nozzle *t*, which it partly incloses and beneath which is a cup holder *35*. The end of the nozzle is protected by a shield *u* fastened to the casing.

The valve casing *m* is provided with two valve seats *v* and *w* and a double-faced valve *x*, above the top of which extends a pilot valve *z* adapted to control passage *y* and facilitate the seating of the main valve 95 on seat *v*. It will be seen that when the valve is in its lower position its lower face will seat on seat *w*, closing communication between cylinder *h* and nozzle *t*, while its upper face and the pilot valve will be clear 100 of seat *v* and passage *y* affording communication between cylinders *c*, the carbonated water supply *e*, and cylinder *h*, and vice versa. A plug is threaded onto the head of

valve casing *m* and may be removed for cleaning the valve.

A valve stem 3, integral with valve *x*, extends out of the casing through a stuffing box 4 and is fitted on the end with a yoke 5. The yoke carries a spring-pressed tappet having a roller 6 on its end. Valve *x* is drawn into lower position by means of a spring 7 connected to bracket 8. Beneath the roller is a horizontal shaft 10 carried by bracket 8 in suitable bearings. Pinned to the shaft is a cam 13 adapted to act on the roller 6 and raise the valve against the action of spring 7, which, when the high point of the cam passes out of contact with the tappet, returns the valve to its lower position. A second cam 14 is pinned to the shaft and adapted to act on a block 15, provided with a roller 16 and slidable on the bracket 8, against the action of a spring 17, carried by a pin 18 in the frame and connected to a pin 19 extending from the block.

A pinion 20 is sleeved on the shaft 10, the sleeve being connected with the shaft, in one direction through the action of a pawl 21, carried by the sleeve, on ratchet 22 carried by the shaft.

The flavoring syrup containing, measuring and delivering element, comprising a container 23, provided with a removable cover 24, and a false bottom 25, is suitably fastened to a frame 26.

A well 27, provided with a passage 28 flush with the false bottom, is positioned in the bottom of the container.

A plunger 29, having a stem 30, is fitted into the well, and a pipe 31 leads from near the bottom of the well through the plunger and through the casing *a*, terminating in a plain nozzle 12 adjacent to the carbonated water nozzle *t*, beneath shield *u*. A lever 32, pinned to a fulcrum 33, is connected at one end to the end of plunger stem 30 and at the other end, through a pin and slot, to a plate 34, suitably secured to the end of shaft 10.

The coin-connected manually operated actuating mechanism for delivering the syrup and carbonated water comprises a rack bar 50 in engagement with pinion 20. An ori-ficed block 67 surrounds the end of the rack bar and contains a coin slot at an angle therein just beyond the end of the inclosed bar. This block is adapted to be slid along the top of a coin chute 68 by a hand lever 72 pivoted to a suitable support and having an arm connected with the block by slot and pin connection 69.

Ordinarily, block 67 slides freely on the rack bar without moving it. When a coin is entered into its coin slot, however, the coin, being larger in diameter than the rack bar, forms a stop and in the movement of the block the bar is also moved, turning

pinion 10 and operating the dispensing 65 valve.

Chute 68 has an elongated opening 70 in its top face, underlying block 67 in its movement by the hand lever. This opening 69 is of such width for most of its length that it will not permit the passage of the coin in the slot of block 67 until the block has been moved to complete its dispensing function. At the final position of the block, opening 70 is widened as shown at 70', Fig. 6, and the coin falls into the chute. Opening 70 also serves the purpose of allowing coins smaller than the coin with which the machine is intended to be used to fall directly from the slot in the block and prevent such other coin acting to cause the dispensing to take place.

After the block has been made to travel as described, it returns to its initial position when the hand lever is released. Rack bar 66 is also returned to its initial position by providing a slot 66' in the bar adapted to act with a pin 71 in the block to allow free movement of the block when moved without any coin being entered.

An arm 74 extends from the lever to which one end of a spring 75 is fastened, the other end being fastened to the frame, to return and maintain the lever in its initial position as shown in Fig. 2.

A ratchet 76 is formed on the lever adjacent the pivot having at one end a stop 77 and at the other end a pawl trip 78. A pawl 79 is pivoted to a suitable support in position to act on the ratchet 76 as the handle 100 descends, until the trip acts to throw it out of engagement, when the handle reaches its lower limit. A detent pin 80, held in place by a spring 81, engages the short arm of the pawl and holds it in engagement with the ratchet until the pawl is tripped. The detent then holds the pawl out of its ratchet engaging position until the handle is raised and the stop 77 throws the pawl back into engagement with the ratchet.

Pivoted to the block engaging arm of lever 72 is a forked rod 83 engaging the shaft 10 with its forked end and having a shoulder 84 formed on its side to act as a stop for shaft 10 through the medium of arm 85 carried by cam 14 and positioned to contact with the arm when the rod 83 is fully advanced by the lever reaching its lower position. A dash pot 86 is positioned adjacent the lever 72 and connected with the block 120 engaging arm to regulate the speed at which the lever may be moved.

A coin duct 90, which is adapted to receive a coin released from the cup dispensing mechanism (not shown) extends downward to a point just above the coin slot in block 67. A leaf spring 91 having a flange 92 at one end is fastened to the coin receptacle 68

and extends upwardly in such a position that when the block is not in position to receive a coin the flange will be under the end of the coin duct and will prevent a coin from 5 coming out. When the block is returned to the coin receiving position the spring is pushed out of the way and the coin may drop into the coin slot.

To prepare the machine for operation, the 10 valve *g* is opened, connecting the carbonated water supply with the horizontal tanks *c*, and plunger *i* is adjusted in cylinder *h* so as to adapt the cylinder to receive the desired quantity of carbonated water. The 15 stroke of plunger 29 is adjusted, by adjusting lever 32 on plate 34, to pump the required quantity of syrup.

Cam 13 is positioned to elevate the valve *e* and thus shut off the connection between 20 the carbonated water supply and the measuring cup *h*. The roller 16 on block 15 is at the low point of cam 14.

The cup is placed in the holder 35 on the outside of the casing, beneath the syrup 25 nozzle and carbonated water nozzle.

Assuming that a coin has passed down the coin duct 90 into the coin slot in block 67, and that the lever 72 is then pulled downward, as heretofore explained, this movement of lever 72 rotates shaft 10, through pinion 20, pawl 21 and ratchet 22. As shaft 30 turns, lever 32 is actuated and causes plunger 29 to force syrup from well 27, up pipe 31, and into the cup and causes the 35 plunger to again rise, permitting the well to refill.

The rotation of shaft 10 causes cams 13 and 14 to turn. The high point of cam 13 moves away from roller 6, permitting valve 40 *x* to assume its lower position on seat *w* under the influence of spring 7, opening communication between the cylinder *h*, which acts as a measuring cup, and the tanks *c* through passage *y* in the valve casing and 45 pipe *n*, causing the measuring cup to fill with carbonated water.

Cam 14 turns on roller 16, forcing block 15 down and tensioning spring 17.

The rack advances turning the shaft 10 and the cams as above described until the cams assume the position shown in Fig. 7, with cam 13 about to raise roller 6 on the valve tappet and the roller 16 about to leave the high point of cam 14. In the movement 55 of the hand lever, the forked rod 83 is advanced so that a light continued movement of shaft 10 will cause arm 85 to contact with shoulder 81 and stop further movement.

A slight further movement of the rack 60 causes block 15, under the influence of the tension set up in spring 17, to kick cam 14 around, as roller 16 goes off the high point of the cam, causing cam 13 to raise valve *x*, seating it on seat *v* and causing pilot 65 valve *z* to close off passage *y*, at the same

time opening communication between the cylinder *h* and nozzle *t*, allowing the carbonated water in the cylinder to discharge into the cup and mix with the syrup. When roller 6 is on the high point of cam 13, arm 70 85 contacts with shoulder 84 and motion stops.

The coin drops through slot 70' into chute 68 leading to any convenient receptacle.

During the descent of lever 72 the pawl 75 79 engages ratchet 76, preventing the lever from being raised until it reaches the bottom of its stroke, when the pawl is tripped out of action by means of the tripper 78.

The lever 72 is returned to its initial position by means of spring 75 and the pawl put in action by stop 77, which engages it, as the handle reaches its initial position. It will be noted that when the lever is moved down it must be moved all the way down and the 85 coin dropped out before it can be again raised, thus preventing any more than one portion of syrup and water being obtained with one coin.

The muffler *q* and arrangement of the nozzle *t* in pipe *s* prevents the water from 90 splashing and spitting out of the nozzle *t*.

When it becomes necessary to wash out the machine, this may be done by attaching a hose to valve *o*, opening the valve and 95 turning on a supply of water.

Having now fully described my invention, what I claim and desire to protect by Letters Patent is:

1. In a dispensing apparatus, the combination of a measuring device, a source of supply, a delivery nozzle, a spring-tensioned valve adapted to connect the measuring device alternately with the source of supply and with the delivery nozzle, spring actuated mechanism adapted to position said valve to shut off the supply, and manually operated mechanism adapted to permit said valve to open the supply, under the action of its spring, and adapted also to render the spring actuated mechanism operative. 100

2. In a dispensing apparatus, the combination of a measuring device, a source of supply, a delivery nozzle, a valve adapted to connect the measuring device alternately with the source of supply and with the delivery nozzle, a cam adapted to act on the valve to position it to close communication between the supply and the measuring cup, a spring adapted to cause the cam to so act, 115 and manually operable mechanism adapted to release the cam from the valve and permit it to open communication between the measuring cup and the source of supply and at the same time put tension on said spring. 120

3. In a dispensing apparatus, the combination of a measuring device, a source of supply, a delivery nozzle, a valve controlling communication between the measuring device and the source of supply and the de- 130

livery nozzle, spring actuated mechanism adapted to actuate said valve to cut off communication between the supply and the measuring device and open communication 5 between the measuring cup and the delivery nozzle, and manually operable mechanism to release said valve and allow it to open communication between the supply and the measuring cup and shut off communication 10 between the measuring cup and the delivery nozzle.

4. In a dispensing apparatus, the combination of a measuring cup, a source of supply, a delivery nozzle, a valve adapted to 15 open communication alternately between the measuring cup and the supply and the measuring cup and the delivery nozzle, of a cam shaft, a cam on said shaft adapted to actuate said valve to close communication 20 between the supply and the measuring cup, a second cam on said shaft, a spring adapted to be tensioned by the second cam and then to actuate the second cam and thereby turn the shaft to cause the first cam to act, 25 and a rack and pinion adapted to rotate said cam shaft to operate to release said valve and permit it to open communication between said supply and measuring cup and to operate the said second cam to tension 30 said spring and be actuated thereby.

5. In a dispensing apparatus, the combination of a measuring cup, a source of supply, a delivery nozzle, a valve adapted to open communication alternately between the 35 measuring cup and the supply and the measuring cup and the delivery nozzle, a cam shaft, a cam on said shaft adapted to actuate said valve, a second cam on said shaft, a spring adapted to be tensioned by the sec- 40 ond cam and then to actuate the second cam and thereby cause the first cam to act, a manually operable handle, means operable thereby to turn the cam shaft, means operating in the downward stroke of the handle 45 to prevent its being raised, and means operating at the bottom of its downward stroke to render said means inoperative.

6. In a dispensing apparatus, the combination of a measuring device, a source of

supply under pressure, a delivery nozzle, a 50 valve adapted to connect the measuring device alternately with the supply and the delivery nozzle, a valve casing having a transverse passage in communication with the supply, a pilot valve connected to said 55 first mentioned valve and adapted to open and close said passage, spring actuated mechanism adapted to positively position said valves to shut off the supply, and manually operable mechanism adapted to release said valves and permit them to open communication between the supply and the measuring cup.

7. In a dispensing apparatus, the combination with liquid dispensing mechanism, 65 of a manually operable handle, operative connections between said handle and the liquid dispensing mechanism, a ratchet carried by the handle, a pawl engaging said ratchet, a detent positioning the pawl in operative position, a pawl trip adapted, as the handle completes its movement in one direction, to displace the pawl, and a stop adapted, as the handle completes its movement in the other direction, to restore the pawl to 70 operative position.

8. In a dispensing apparatus, the combination with a measuring cup, an upright valve chamber, a discharge nozzle, a channel extending obliquely downward and communicating with the measuring cup, with the valve chamber and with the discharge nozzle, a source of liquid supply connected with the valve chamber, a valve movable in said chamber and adapted in one position to 80 connect the supply with the part of the channel connected with the measuring cup and shut off communication between such part of the channel and the part thereof connected with the discharge nozzle and in 85 another position to shut off the supply and open the channel, and manually controlled 90 means to actuate the valve.

In testimony of which invention, I have hereunto set my hand, at Philadelphia, Pa., 95 on this 28th day of November, 1919.

JOHN FRICK.
